EAR RINGS OR SIMILAR ARTICLEMadge H. Pizzano and Charles W. Pizzano,
Marblehead, Mass.

Application August 8, 1947, Serial No. 140,776

Term of patent 3½ years

(Cl. D45—16)

To all whom it may concern:

Be it known that we, Charles W. Pizzano and Madge H. Pizzano, both citizens of the United States of America, and both residing at Marblehead, County of Essex, and Commonwealth of Massachusetts, have invented a new, original and ornamental Design for Combined Necklace And Ear Rings or Similar Article, of which the following is a specification, reference being had to the accompanying drawing forming a part thereof.

Fig. 1 is a front view partially in perspective of a combined necklace and ear rings showing our new design, the front of one and the reverse of the other ear ring element being shown; and

Fig. 2 is a top plan view of the combined necklace and ear rings in position for wearing.

We claim:

The ornamental design for a combined necklace

and ear rings or similar article, substantially as shown.

MADGE H. PIZZANO.
